(No Model.)

E. HERDEGEN.
FLUSH VALVE FOR WATER CLOSETS.

No. 485,155.

Patented Oct. 25, 1892.

UNITED STATES PATENT OFFICE.

EDUARD HERDEGEN, OF NEW YORK, N. Y., ASSIGNOR TO CASSIDY & ADLER,
OF SAME PLACE.

FLUSH-VALVE FOR WATER-CLOSETS.

SPECIFICATION forming part of Letters Patent No. 485,155, dated October 25, 1892.

Application filed May 11, 1892. Serial No. 432,571. (No model.)

To all whom it may concern:

Be it known that I, EDUARD HERDEGEN, a subject of the Emperor of Germany, residing in the city of New York, county and State of New York, have invented a new and useful Improvement in Flush-Valves for Water-Closets, of which the following is a specification.

The object of my invention is to provide an additional flush-valve for water-closets, whereby when the ordinary flush-valve generally in use is closed a specified amount of water will at once continue to flow through the closet while being used.

The invention consists in the improved flush-valve and the arrangement and combination of its various parts and its connection with the valve-operating mechanism, substantially as hereinafter described and claimed.

Referring to the drawings, in which like letters indicate similar parts, Figure 1 is a longitudinal vertical section of a water-tank on line 1 1, Fig. 2, a portion of the water-pipes and flush-valves being also shown in section; and Fig. 2 is a partial top view of the tank.

In the drawings, A represents a water-tank divided by a vertical partition B into two chambers C D, the partition B extending nearly to the top of the tank, so as to leave an overflow-opening E from the receiving-chamber D.

Upon a bar F, extending across the top of the tank or other support, is secured in any desired manner an upright G, on which is fulcrumed a lever H, pivoted at one end with an adjustable weight I, the other end being adapted to be connected with a rod or chain J, the lower end of this rod or chain being preferably connected to the seat of the water-

closet. Water enters the receiving-chamber D through a pipe K, and the height of water in this chamber is regulated by an ordinary ball-valve in the pipe K or by analogous means, but not shown in the drawings.

To the arm H' of the lever H is connected a rod or chain L, to the lower end of which is secured a valve M, adapted to open and close the valve-seat in the bottom of the chamber C, which valve-seat is at the top of the main flushing-pipe U.

Extending from the chamber C into the

lower part of the chamber D through the partition B is a small chamber P. In the plate forming the top of the chamber P is an aperture leading into the chamber D, which is opened and closed by means of a valve (not shown) connected by rod R with the arm H² of lever H. This valve and connecting-rod are inclosed in a pipe S, rigidly secured over the aperture in the top plate of the chamber P. The main pipe U is connected by a coupling T with a pipe O, extending to the chamber D and opening into a vertical pipe a within the chamber D. The upper end of pipe a is or may be threaded to receive a threaded valve-seat c, having cross-bar d with central opening to guide a valve-stem e; but the valve-seat c and bar d may be directly on pipe a.

f is a disk-valve adapted to rest upon the cross-bar d when the valve is closed, as shown in Fig. 1. A short distance above the disk f is a larger disk g, adapted to rest upon the top edge of the valve-seat c and forming between the disks f and g an annular channel, in which is or may be placed a water-tight packing h. The disk g is secured to the lower end of an upright tube or rod j, which is contained within a vertical shell k and adapted to slide vertically therein. The upper part of this shell k is by preference closed by means of a cap m. The extent of movement of the shell k on the valve-holder j, or vice versa, is controlled by a vertical slot n in the side of the tube j, which receives a screw or pin o, secured in the shell k. The top of the cap m connects by a rod or chain p with the arm H² of the lever H.

In the position shown in Fig. 1 the water-closet seat is unoccupied, the valve M being opened and the valves in pipes S and a closed. In this condition the water in the chambers C and P will pass through the pipe U into the water-closet basin, and meanwhile the chamber D will be filled to its predetermined height through the pipe K. When the rod or chain J is drawn down by pressure on the water-closet seat or by any other means, the arm H' of the lever will be moved downward, closing the valve M, while the arm H² will be moved upward, opening the valve in pipe S and lifting the shell k and valve-holder j. In

this position, therefore, the valve M will be closed and the valves in the pipes S and a will be opened. Water will then flow through chamber P into chamber C. The valve g on the pipe a being also open, water will also flow through the opening formed between the disk g and valve-seat c into pipe a and thence through pipes O and U to the water-closet basin. When the pressure on the seat is removed, the lever H will at once resume the position shown in Fig. 1. The shell k will also be lowered and the valve-holder j within it will gradually slide down until its valve g finally rests on the seat c. The valve M being opened at the same time, the water in the chamber C will pass through pipe U to the water-closet basin.

By my improved flush-valve I am enabled to flush the closet-basin while the closet is in use and the seat is pressed down instead of the flushing being confined to the time when the pressure on the seat is removed—that is to say, as soon as the seat is occupied water will flow through the pipes a O U into the basin. At the same time by opening the valve in S the chamber C will be filled, and when afterward the seat is released the water will be gradually shut off by closing the valve g, while the full flushing process is secured by the opening of the valve M. This feature of allowing the valve g to be gradually closed is a valuable part of my invention and is accomplished by the water rushing through or between the valve-seat c and the vertically-movable valve g, thereby partially support-

ing it and allowing it to only slowly regain its seat, which is not accomplished until some time after the shell k, together with the lever-arm H², attached thereto, have attained their normal position, whereby it will be seen that for some time after the seat or arm H' is released the water will continue to flow from the chamber D, or even after the entire contents of the chamber C has been drawn off.

Having described my invention, what I claim, and desire to secure by Letters Patent, is—

1. The combination of tank A, having partition B and chambers C, P, and D, with the water-discharge pipe U, valve M thereon, branch pipe O, carrying upwardly-extending pipe a, shell k, valve g, loosely carried therein, whereby said valve g will not be seated until after the shell k and lever-arm attached thereto have regained their normal position, and valve-chamber S, having a valve mounted therein, substantially as herein shown and described.

2. The combination of the pipe a with the valve g, adapted to close its upper end, shell k, valve-stem j, adapted to slide therein, and lever H, attached thereto, all arranged so that the valve g will be unseated after the shell k has regained its normal position, substantially as herein shown and described.

EDUARD HERDEGEN.
